GARMENT HANGER

Blythe O. Blades, Los Angeles, Calif.

Application May 14, 1945, Serial No. 593,731

9 Claims. (Cl. 223—91)

1

This invention relates to a garment hanger. More specifically speaking, the invention pertains to that type of garment hanger which is adapted to suspend, in an extended condition and from a single hook, a complete suit consisting of a coat, a vest and a pair of trousers.

It is an object of the invention to provide, in a hanger of the kind just stated, an improved combination of rigid suspending frame designed for supporting a coat and vest in an extended condition, an accessory clamping member connectable with said frame in such a manner as to be usable to clamp a pair of trousers or other garment supported on the frame, thus to safeguard against such garment becoming dislodged from its supported position.

Another object is to provide a garment hanger of the hook-supported loop type with an improved detachable garment-gripping means whereby one or more garments supported by the hanger will be securely held thereon while being transported, for example, to and from a cleaner's shop.

Additional objects relate to extreme simplicity of structure and to an improved means for detachably connecting the clamping bar to the main hanger member.

Other objects, advantages and features of invention will hereinafter appear.

Referring to the accompanying drawing which illustrates what at present is considered to be a preferred embodiment of the invention,

Fig. 1 is a perspective view wherein the hanger is completely shown, but on a smaller scale than in the remaining views, the lower portion of a garment supported thereby being broken away in order to contract the view.

Fig. 2 is a perspective view of the hanger per se upper and intermediate portions thereof being broken out in order to contract the view.

Fig. 3 is a plan view of the structure shown in Fig. 2, except that parts are shown in section.

Fig. 4 is a perspective view showing two fragments of the hanger, one of said fragments having through it a locking aperture and the other a male locking member insertable into said aperture and turnable therein to a locked position.

Referring in detail to the drawing, the main hanger member 5 comprises an elongated strap metal loop having an upper run 6 furnished centrally with a suspending hook 7, the outer end portions of this run being shown downwardly inclined to some extent to the points where they join the relatively short, vertical end runs 8. The lower run 9, unlike the remaining portion of

2

the loop 5, has its breadth extending vertically when the device is in its suspended position, this positioning of said run 9 being accomplished by giving it a ninety degree twist adjacent to its ends as indicated at 10 and 11. It is an advantage to position said lower run 9 in the manner just stated so that the trousers 12 or any other garment may be more conveniently looped therearound, but it is immaterial whether or not the twists 10 and 11 are located at the precise point shown. They would produce the same result if located in the lower portions of the runs 8.

That end portion of the loop member 5 which is furnished with the twist 11 is provided beyond the latter twist with a part 14 which abuts flatwise against and is spotwelded to the adjacent end portion of the aforesaid horizontal run 9, and this part terminates in an outwardly directed latch hook 15 having an upwardly directed nose 16, the concavity or recess in the hook formed by making a substantially rectangular cut-out 17 in the upper edge portion of the strap metal adjacent to said nose 16.

A garment-gripping strap metal arm 18 is provided to cooperate with the lower run 9 of the loop member 5, this arm having at one end a narrowed hasp portion 19 positioned for latching onto the hook 15, the narrowing of this end portion of the arm 18 being effected by making a rectangular corner cut-out 20 into its lower edge. Said hasp portion 19 is deflected outwardly to cause it to cooperate more efficiently with the hook 15.

The bar 18, adjacent to the end thereof opposite to its hasp 19, is provided with a T-shaped extension consisting of a neck portion 21 and a flattened head 22, this extension being thus shaped by reason of opposed rectangular cut-outs 23 being cut into opposite edges of this part 40 of the strap metal. The neck 21 is right-angularly bent at about its midlength so as to offset the head 22 in the manner shown, in order that said head may interlock within a longitudinal slot 25 provided in the midwidth portion of the strap metal run 9 adjacent to its twist 10. The head 22 includes ear portions 22a which are deflected oppositely to the direction in which the outer part of the neck 21 is deflected. When said head is in an interlocked relation to the slot 25 55 the arm 18 may be given a universal swinging movement of considerable extent without it becoming detached from the run 9 of hanger.

It will now be evident that, after a garment has been looped around the longitudinal run 9, the garment-gripping arm 18 may be put in place to

grip such garment between said arm and said horizontal run. This will be accomplished by holding the arm 18 with its neck 21 and head 22 directed either upwardly or downwardly in either of which positions said head may be inserted through the slot 25 and the arm then swung to a horizontal position in relation to the device in the suspended position, the hasp portion 19 of the arm then being crowded in behind the nose 16 of the hook 15.

It will also be seen that the hasp portion 19 of the mounted clamp arm 18 may readily be moved upwardly out of the locked position by the thumb or a finger of the same hand that is gripping and supporting the hanger, thus releasing a gripped garment so that it may be removed by the other hand of the operator. As a result of the offset positioning of the hanger portions 15 and 22 there is provided between the mounted arm 18 and the horizontal hanger run 9 a clearance of sufficient width to accommodate a single thick garment or several thinner ones. Also the resiliency of the hanger portions at each side of this clearance permits its width to be increased, if necessary. In Fig. 3 the dotted lines show the outswung position of the parts 9 and 18 when a garment of considerable thickness is gripped between them.

What is claimed is:

1. In a garment hanger, an elongated strap metal loop furnished with an upper run carrying a suspending hook, a downwardly directed relatively short run at each end of said loop, a horizontal run connecting the lower ends of said end runs, the strap metal of said loop being twisted adjacent to the lower ends of said end runs in such a manner as to position the breadth of said horizontal run in substantially a vertical plane, and a detachable garment-gripping arm having a keyhole and key connection with one end portion of said horizontal run and a latching connection with the opposite end portion of said horizontal run, said key being so bent as to bring its terminal portion into a laterally offset relation to the arm which supports it, whereby to space apart said arm from said horizontal run.

2. In a garment hanger, an elongated strap metal loop furnished with an upper run carrying a suspending hook, a downwardly directed relatively short run at each end of said loop, a horizontal run connecting the lower ends of said end runs, the strap metal of said loop being twisted adjacent to the lower ends of said end runs in such a manner as to position the breadth of said horizontal run in a substantially vertical plane, said horizontal run having a longitudinal slot in one of its end portions, and a garment-gripping arm having at one end a deflected extremity that terminates in a locking head, said head being insertable through said slot and assuming a locking relation thereto when the arm is swung into a parallel relation to the aforesaid horizontal run, said arm having a latch-on connection with the opposite end portion of said horizontal run.

3. In a garment hanger, an elongated strap metal loop furnished with an upper run carrying a suspending hook, a downwardly directed relatively short run at each end of said loop, a horizontal run connecting the lower ends of said end runs, the strap metal of said loop being twisted adjacent to the lower ends of said end runs in such a manner as to position the breadth of said horizontal run in a substantially vertical plane, said horizontal run having a longitudinal slot in one of its end portions, and a garment-gripping

strap metal arm having a recess in each side edge thereby forming a neck furnished at its outer end with a flat head which projects from both edges of said neck, said neck being bent so as to bring said head into a laterally offset relation to the arm, said head being insertable through said slot and assuming a locking relation thereto when the arm is swung into a parallel relation to the aforesaid horizontal run, said arm having a latch-on connection with the opposite end portion of said horizontal run.

4. A garment hanger comprising a main hanger member carrying a suspending hook and including a horizontal run, said horizontal run having a slot in one of its end portions, and a clamping bar consisting of a garment-gripping strap metal arm having a recess in each side edge thereby forming a neck furnished at its outer end with a flat head which projects from both edges of said neck, said neck being bent so as to bring said head into a laterally offset relation to the arm, said head being insertable through said slot and assuming a locking relation thereto when the arm is swung into a parallel relation to the aforesaid horizontal run, said arm having a latch-on connection with the opposite end portion of said horizontal run.

5. The combination with a suspendable hanger having a horizontal run provided with a slot in one of its end portions; of a detachable clamping bar consisting of a garment-gripping arm having a key formed upon one of its end portions and insertable into said slot to maintain said bar in a universally movable locked relation thereto, said key being the terminus of a neck working in said slot which unites said key and arm, said neck being bent so as to bring said key into a laterally offset relation to the arm, that end portion of said arm which is opposite to its said key having a latch-on connection with said horizontal arm to maintain said arm in a garment-gripping position.

6. In a suspendable hanger having a horizontal run, a garment-gripping bar, means to connect one end portion of said bar with one end portion of said horizontal run in a universally swingable manner, said means comprising a locking head forming a deflected extremity of the universally connected end of said bar and having a locking relation with said run when the arm is swung into a parallel relation therewith, and an upwardly directed hook carried by that end portion of said horizontal run which is opposite to its connection with said bar, said bar carrying a latch element at its free end seatable in said hook to maintain said arm in a garment-gripping position in cooperation with said horizontal run, a slight upward movement of the free end of said arm sufficing to release it from said hook.

7. A garment hanger comprising a main hanger member carrying a suspending hook and including a horizontal run, said horizontal run having a slot in one of its end portions, and a garment-gripping arm having at one end a deflected extremity that terminates in a locking head, said head being insertable through said slot and assuming a locking relation thereto when the arm is swung into a parallel relation to the aforesaid horizontal run, said arm having a latch-on connection with the opposite end portion of said horizontal run.

8. In a garment hanger, an elongated strap metal loop furnished with an upper run carrying a suspending hook, a downwardly directed relatively short run at each end of said loop, a horizontal

zontal run connecting the lower ends of said end runs, the strap metal of said loop being twisted adjacent to the lower ends of said end runs in such a manner as to position the breadth of said horizontal run in a substantially vertical plane, said horizontal run having a longitudinal slot in one of its end portions, and a clamping bar consisting of a garment-gripping strip metal arm having a recess in each side edge thereby forming a neck furnished at its outer end with a flat head which projects from both edges of said neck, said neck being bent so as to bring said head into a laterally offset relation to the arm, said head being insertable through said slot and assuming a locking relation thereto when the arm is swung into a parallel relation to the aforesaid horizontal run, said arm having a latch-on connection with the opposite end portion of said horizontal run.

9. A garment hanger comprising a main hanger member carrying a suspending hook and including a horizontal run, said horizontal run having a slot in one of its end portions, and a clamping bar consisting of a garment-gripping strap metal arm having a recess in each side edge thereby forming a neck furnished at its outer end with a locking terminal, said neck being bent so as to

10

15

20

25

bring said locking terminal into a laterally offset relation to the arm, said locking terminal being insertable through said slot and assuming a locking relation thereto when the arm is swung into a parallel relation to the aforesaid horizontal run, said arm having a latch-on connection with the opposite end portion of said horizontal run.
